(57) **CLAIM**

The ornamental design for a self-service terminal, as shown and described.

DESCRIPTION

FIG. 1 is a perspective view of a self-service terminal showing our design;

FIG. 2 is an enlarged partial perspective view of the self-service terminal shown in FIG. 1 from below line 1, shown with portions of the article in an illuminated state;

FIG. 3 is a left side view of the self-service terminal shown in FIG. 1;

FIG. 4 is a right side view of the self-service terminal shown in FIG. 1;

FIG. 5 is a front view of the self-service terminal shown in FIG. 1;

FIG. 6 is a back view of the self-service terminal shown in FIG. 1; and,

FIG. 7 is a top view of the self-service terminal shown in FIG. 1.

The thicker, larger dash-dot-dash broken line seen in FIGS. 1 and 2, labeled “1”, is a crop line in reference to the enlargement view, and forms no part of the claimed design. The smaller, finer dash-dot-dash broken lines represent illumination and form no part of the claimed design. All other broken lines depict portions of the self-service terminal which form no part of the claimed design.
